FIG.1

FIG.6

FIG.2

FIG.3

FIG.4

FIG.5

FIGURE 1 is a perspective view of one combination chair-desk embodying our new design;

FIGURE 2 is a side elevational view thereof;

FIGURE 3 is a front elevational view thereof;

FIGURE 4 is a bottom plan view thereof;

FIGURE 5 is a rear elevational view thereof; and

FIGURE 6 is a perspective view of another combination chair-desk embodying our new design. The combination chair-desk shown in FIGURE 6 is the same as the combination chair-desk shown in FIGURES 1-5 with the exception that the FIGURE 6 legs are tapered adjacent their lower ends, whereas the FIGURES 1-5 legs are substantially straight.

The dominant features of our design reside in those portions shown in full lines in the drawings.

We claim:

The ornamental design for a combination chair-desk, substantially as shown and described.
